QUIVER

Franklin E. Adams, 12891 Chaparral,
Garden Grove, Calif. 92640

Filed Jan. 27, 1971, Ser. No. 110,360

Term of patent 14 years

Int. Cl. D22—04

U.S. Cl. D22—13

FIG. 1.

FIG. 2.

FIG. 3.

FIG. 4.

FIG. 6.

FIG. 5.

FIG. 1 is a perspective view of a quiver showing my new design;

FIG. 2 is an elevational view of the side opposite that shown in FIG. 1;

FIG. 3 is an end elevational view thereof as seen from the right of FIG. 2;

FIG. 4 is a cross-sectional view taken on line 4-4 of FIG. 2;

FIG. 5 is an enlarged cross-sectional view taken on line 5-5 of FIG. 5, being fragmentarily shown for convenience of illustration; and

FIG. 6 is a bottom plan view thereof.

I claim:

The ornamental design for a quiver, as shown and described.
